Primary Examiner — T Chase Nelson*Assistant Examiner* — Jonathan J. Han(74) *Attorney, Agent, or Firm* — Michael S. Hargis; King & Schickli, PLLC(57) **CLAIM**

The ornamental design for a foot for a jack assembly, as shown and described.

DESCRIPTION

FIG. 1 is a perspective view of a foot for a jack assembly showing our new design;

FIG. 2 is a top view thereof;

FIG. 3 is a front view thereof;

FIG. 4 is a rear view thereof;

FIG. 5 is a right side view thereof; and,

FIG. 6 is a left side view thereof.

The broken lines depict environment and form no part of the claimed design.

1 Claim, 4 Drawing Sheets(56)
